UNITED STATES PATENT OFFICE.

CLARENCE M. FLORA, OF OKLAHOMA CITY, OKLAHOMA.

FOLDING REVERSIBLE FRENCH CUFF.

Application filed August 1, 1923. Serial No. 655,118.

To all whom it may concern:

Be it known that CLARENCE M. FLORA, a citizen of the United States, residing at Oklahoma City, in the county of Oklahoma and State of Oklahoma, has invented new and useful Improvements in Folding Reversible French Cuffs, of which the following is a specification.

The present invention has for its purpose 10 to provide a folding cuff commonly known as a French cuff and which may be constructed for permanent attachment to the sleeve or for detachable connection with the sleeve. In either use, the cuff may be reversed or made relatively stiff or semi-stiff 15 owing to inner reinforcements arranged between the inner and outer layer of the cuff in order to attain this result.

Another purpose is to provide an inner 20 reinforcement which, in some instances, may correspond to the full length and width of the cuff with an extra relatively stiff reinforcement extending half the width of the cuff, thereby constituting means acting as a 25 guide for determining the line of fold of the cuff so as to cause the button-holes in the cuff to properly register when applying cuff buttons. In order to provide a cuff which is relatively semi-stiff, the reinforcement 30 which extends the entire length and width of the cuff may be dispensed with. In this instance, the stiffening or reinforcement which extends half the width of the cuff remains, thereby providing a relatively stiff 35 inner portion of the cuff next to the wrist. In this case, the reinforcement also acts as a guide on which the cuff may properly fold in order to make the cuff buttons register. A cuff of this kind may be laundered with 40 or without starch. Obviously, if starch is used, the reinforced wrist-band portion of the cuff will hold the folded part of the cuff, even though it is semi-reinforced, in proper position and thereby present a smooth but 45 soft appearance. However, if the semi-reinforced cuff is starched, the reinforced wrist-band portion of the cuff will be relatively stiff while the folded part will have a very soft appearance. In this way, the 50 starched wrist-band portion will stand away from the wrist and will not be uncomfortable to the wearer as is the case when the cuff is not starched at all.

Another purpose is to provide a French 55 folder cuff which, when worn, the ends thereof overlap so that the button-holes will

register to receive the ordinary straight shank cuff button in lieu of a cuff where the ends are brought together with the inner faces of the ends adjacent each other to receive what is known as a link cuff button whereby the ends project.

A further purpose is to provide an inner reinforcement, a portion of which conforms to that portion of the cuff which folds back 60 while the other portion thereof corresponds to the wrist-band portion of the cuff. This latter portion is considerably heavier than the portion which folds back with the folding portion. Furthermore, this latter portion is shorter than the wrist-band and is adapted to act as a guide in order that the cuff may accurately fold to bring the button-holes in register without the fold being 65 pressed or ironed.

It is to be understood that the particulars herein given are in no way limitative and that, while still keeping within the scope of the invention, any desired modifications of detail and desired proportions may be made 70 in the apparatus according to the circumstances.

The invention comprises further features and combinations of parts to be hereinafter set forth, shown in the drawings and 75 claimed.

In the drawings:

Figure 1 is a view in perspective of the improved folder French cuff constructed in accordance with the invention and as a 80 permanent attachment to the sleeve of a shirt.

Figure 2 is a sectional view through the same on line 2—2 of Figure 1, showing the construction of the cuff and showing how it 85 is attached to the shirt sleeve, also showing the wristband starched and relatively stiff.

Figure 3 is a plan view of the cuff straightened out, showing the different thicknesses broken away in order to show 90 the construction of the number of pieces used for making up the cuff.

Figure 4 is a view of a folder French cuff as a separate part from the shirt sleeve and disclosing the fact that the wrist-band is 95 laundered soft and with the ends of the cuff overlapped.

Figure 5 is a cross sectional view on line 5—5 of Figure 4.

Figure 6 is a perspective view of the 110 form of cuff shown in Figure 4 but showing the wrist-band laundered stiff.

Figure 7 is a plan view of the cuff disclosed in Figures 4 and 6, showing the same as a separate part from the shirt sleeve and illustrating the different thicknesses of the cuff broken away.

Referring particularly to Figures 1 to 3, inclusive, of the drawings, 1 designates the sleeve of a shirt to which the cuff 2 is attached. The cuff comprises four thicknesses 10 for the wristband which is the inner half of the cuff. The thickness 3 is of a width and length to correspond to the entire width and length of the cuff. This thickness lies adjacent the wrist, that is, for the entire 15 width of the wrist-band of the cuff and faces outwardly when the cuff is folded, as in Figure 1. The layer 4 also corresponds to the full width and length and the outer face of this thickness for the full length 20 of the folded part of the cuff lies against the exterior face of the wrist-band portion of said layer or thickness.

The thickness 5 corresponds to the entire width and length of the cuff and is arranged 25 interiorly of the wall of the cuff. In other words, the inner thickness for half the width of the cuff lies between the thickness 3 and the thickness 4 while the other half of the thickness 5 is interposed between the 30 thickness 4 and an interior stiffening thickness 6 which may be made of any suitable material, such as duck or the like but not too heavy, for instance, just sufficient to provide means to properly starch for the purpose 35 of holding the wrist-band relatively stiff. It will be noted that this interlining or stiffening 6 is of a width slightly less than half the width of the entire cuff, the edge 7 thereof, which is stitched as at 8 to 40 the thickness 3, acting as a guide on which the cuff may be folded. A guide for enabling the outer half of the cuff to properly fold, permits the button-holes 9 to register for the purpose of receiving a straight 45 shank cuff button of the kind where the heads are parallel.

In using the cuff where it is made a permanent part of the shirt sleeve, the lower edge of the sleeve is stitched, as at 10, between the cuff stiffening section 6 and the interlining which extends the full width and length of the cuff. However, before applying the stitches 10, the layer or thickness 4 and the thickness which lies against the thickness 4 are folded inwardly. The stitching 10 is spaced a short distance from where the fold 11 occurs.

The thickness 3 and the cuff stiffening thickness 6 are underfolded but prior to this their edges are stitched to the edge of the shirt sleeve, as shown at 12, and then the stitching 10 is applied. The other margins of the several thicknesses of the cuff are turned inwardly, as shown, and are stitched at 13. The button-holes 9 are made

in the cuff at the proper location so that the cuff may use either link cuff buttons or straight shank cuff buttons, preferably the latter, since it is the aim to provide a French folder cuff, the ends of which may overlap, as shown in Figure 1.

Prior to applying the stitching 13, the opposite thicknesses of the cuff, either in the attached cuff or the detached cuff, are arranged with their inside faces disposed outwardly, their edges being stitched at 13° as in Figures 5 and 6. However, these stitchings 13° do not extend about the entire edges. In fact, a short space for a distance approximately from *a* to *b* as in Figure 7 is left unstitched so that the inside faces of the thicknesses may be disposed inwardly as they should, after which the stitching 13 is applied.

The construction of cuff 2a in Figures 4 to 7, inclusive, is substantially the same as that in Figures 1 to 3, inclusive, with the exception that in Figures 4 to 7 the cuff is separate from the shirt sleeve but it may be attached thereto by means of extra buttons on the wrist-band of the shirt sleeve.

The present invention makes it possible and practicable to use a folded cuff that can be attached or detached, also that can be laundered soft or semi-stiff with the ends adapted to meet and overlap, thus providing a smooth round cuff in appearance. The general construction of the present cuff is practical to the extent that it transforms the double ended stiff cuff into a combination folded cuff, commonly called French cuff. This may be done by using the soft inner lining the full size of the cuff and due to the special cuff-band inner lining terminating a short distance of the exact width of the cuff, the cuff may accurately fold to bring the button-holes in register to permit of the insertion of a straight shank cuff button.

The present form of cuff has stability and weight to the wrist-band portion which constitutes the inner half of the cuff without encumbering the outer half or upturned or folded portion of the cuff. Furthermore, the present form of cuff may present a fluffy, light-weight appearance by leaving the folded part unlaundered without starch and yet at the same time provide a soft strong cuff and one that will permit the fold or bend to be accurately made and that will give a smooth and straight appearance, it being unnecessary to iron or press the cuff in order to provide this fold. The folder French cuff as herein disclosed with the ends meeting and overlapping enables a cuff to be formed and used with a smooth round edge where the fold occurs around the wrist, thereby presenting a neat appearance.

It will be noted that the cuff is capable of being reversed when the folded portion

becomes soiled, preferably in the case of the detached cuff, although it is possible to reverse the cuff which is attached to the sleeve.

The attached cuff is practically the same construction as the detached cuff with the exception that the one is attached to the sleeve and the other is not.

The invention having been set forth, what is claimed is:

- 10 1. A reversible semi-stiff fold cuff comprising two facing sections forming the outside of the cuff, a stiffening lining extending the full length and width of the cuff, and an additional flat stiffening lining extending the full width of the cuff and from the inner edge of the cuff toward and short of the fold line and having an unfolded
- 15

flat edge adjacent the fold line, so that the inner half of the cuff may be stiffened, leaving the outer half soft.

2. A reversible semi-stiff fold cuff consisting of a plurality of thicknesses of fabric extending the full width and length of the cuff, and an additional thickness of fabric constituting a stiffener within the cuff and extending the full width of the cuff and from the inner edge toward the fold and having a flat unfolded terminal edge adjacent to but short of the fold line, whereby the inner half of the cuff may be stiffened with the outer half left soft.

In testimony whereof he affixes his signature.

CLARENCE M. FLORA.
